UNITED STATES PATENT OFFICE.

WILLIAM H. McWILLIAMS, OF KANSAS CITY, MISSOURI.

FOLDABLE BED.

Application filed July 25, 1922. Serial No. 577,274.

To all whom it may concern:

Be it known that I, WILLIAM H. McWILLIAMS, a citizen of the United States, residing at Kansas City, in the county of Jackson 5 and State of Missouri, have invented certain new and useful Improvements in Foldable Beds, of which the following is a specification.

My invention relates to foldable beds and 10 one object is to provide a bed of this character which can be quickly set up for use or folded into compact form for storage or transportation.

A further object is to provide a bed of 15 light weight which, however, is so constructed that when set up for use is braced in such manner as to have ample stability for the support of an occupant, or occupants.

20 Other objects will hereinafter appear, and in order that the invention may be fully understood, reference will now be had to the accompanying drawings, in which:

Fig. 1 is a side elevation of the bed.

25 Fig. 2 is an end elevation of the bed.

Fig. 3 is an end elevation of the bed partly folded and with some of the parts removed.

Fig. 4 is a plan view of the bed.

30 Fig. 5 is a detail perspective view of one of the side rails.

Fig. 6 is a detail perspective view of one of the end rails.

35 Fig. 7 is a broken detail showing the manner in which two braces are pivotally connected together.

Fig. 8 is a broken detail of two stay bars pivotally connected.

In carrying out the invention, I employ 40 four corner posts 2, 4, 6 and 8, the corner posts 2 and 4 being detachably connected at their upper portions by a side rail 10, while the posts 6 and 8 are detachably connected by a side rail 12, Figs. 1 and 4.

The side rail 10 consists of two sections 45 14 and 16 connected by a hinge 18, so that the shorter section 14 may fold against the inner side of the longer section 16, as disclosed by the companion rail 12, Fig. 5. The sections 14 and 16 are held in extended position by a hook 20 pivotally connected to the

50 section 14 and adapted to engage over a nail or screw 22 on the section 16, which is provided at its opposite end with a hinge 24 consisting of two rightangular members 26 and a pintle 28 whereby said members 26 are pivotally connected to the post 4. The sec-

tion 14 is provided at its outer end with a loop 30 adapted to engage over the post 2. The rail 12 is a duplicate of the rail 10, as is evidenced by corresponding reference numerals with exponents "a," the hinge 24^a being connected to the post 6 and the loop 30^a engaging over the post 8.

The posts 2 and 6 are connected at their upper portions by an end rail 32, while the 60 posts 4 and 8 are connected at their upper portions by an end rail 34, Figs. 1, 2 and 4. The end rail 32, Fig. 6, is provided at one end with a hinge 36, which is a duplicate of the hinge 24 and pivotally connected to the post 2, the upturned ends of said hinge 36 being adapted to pass through the loop 30. The end rail 32 is provided at its opposite end with a loop 38 which is a duplicate of the loop 30 and adapted to engage over the 70 post 6 and the upturned ends of the hinge 24^a. The end rail 34 and its fittings are duplicates of the end rail 32 as is evidenced by corresponding reference numerals with exponents "a," the hinge 36^a being pivoted to the post 8 and the loop 38^a being adapted to engage over the post 4.

40 and 42 designate stays spaced below the side rails 10 and 12, respectively. The stay 40 is pivotally connected at its ends to the posts 2 and 4, while the stay 42 is pivotally connected at its ends to the posts 6 and 8. Each stay consists of two sections connected at their overlapping ends by a pivot 44, Figs. 1 and 7, so that the stay may fold with the bed. The overlapping ends of the stay sections have notches 46 to engage over studs 48 at the upper ends of braces 50 and 52. The braces 50 are connected at their lower ends by pivots 54 to the lower portions of the posts 2 and 4 and connected at their upper ends by a pivot 56 which also spaces said upper portions apart to admit the two sections of the stay 40. The braces 52 are connected at their lower ends to the lower 90 portions of the posts 6 and 8 by pivots 58 and connected at their upper portions by a pivot 60 which spaces said upper portions apart to admit the two sections of the stay 42. The braces 52 are connected at their lower ends to the lower 95 portions of the posts 6 and 8 by pivots 58 and connected at their upper portions by a pivot 60 which spaces said upper portions apart to admit the two sections of the stay 42.

61 and 62 designate guard rails, the former being pivotally connected at its ends to the posts 2 and 4 and the latter to the posts 6 and 8. Each guard rail has a pivotal joint 64 intermediate its ends to permit it to fold with the bed.

66 and 68 designate stays similar in con-

struction to the stays 40 and 42. Said stays 66 and 68 are spaced below the end rails 32 and 34, respectively, and the stay 66 is pivoted at its ends to the posts 2 and 6, while 5 the stay 68 is pivoted at its ends to the posts 4 and 8. Each stay has a pivotal joint 70 at its central portion, so that it may fold with the bed.

72 designates a pair of braces connected at 10 their lower ends by pivots 74 to the lower portions of the legs 2 and 6, and connected at their upper portions by a pivot 76 which also spaces said upper portions apart to admit the stay 66 which is provided near its 15 joint 70 with a notch 78 to engage over a stud 80 at the upper portion of one of the braces 72.

82 designates a pair of braces corresponding to the braces 72. Said braces 82 are 20 connected at their lower ends to the legs 4 and 8 by pivots 84, and connected at their upper portions by a pivot 86 which also spaces said upper portions apart to admit the stay 68.

88 designates a mattress consisting, preferably, of a sheet of canvas extending the length and width of the bed and provided at its longitudinal margins with eyelets 90 to receive laces 92 whereby it is suspended from 30 the stays 40 and 42. The ends of the mattress are suspended from bars 94 resting on the ends of the stays 40 and 42.

With the rails, stays and braces arranged as shown and described it is apparent that 35 when the bed is set up that it will have ample stability to support the weight of the occupant, or occupants, as the posts 2, 4, 6 and 8 are firmly braced in all directions.

When desired the bed can be readily folded 40 by successively lifting the loops 30, 38^a, 30^a and 38 from the posts 2, 4, 8 and 6, respectively. The rail sections 14 and 14^a are then folded inwardly against the rail sections 16 and 16^a, so that when the rails 45 10 and 12 are swung downwardly on their hinges 24 and 24^a against the posts 4 and 6, respectively, they will not extend below said posts. The end rails 32 and 34 are then swung downwardly on their hinges 36 50 and 36^a against the posts 2 and 8, respectively. The stays 40 and 42 are then disconnected from the studs 48 and folded downwardly with the guard rails 61 and 62. The braces 50 and 52, respectively, are 55

swung upwardly as the stays 40 and 42 and the guard rails 61 and 62 are swung downwardly to allow the posts 2 and 6 to move towards the posts 4 and 8. The foregoing operation is then repeated with the stays 60 66 and 68 and the braces 72 and 82 to allow the posts 2 and 4 to move towards the posts 4 and 8, respectively, as partly disclosed by Fig. 3. The parts may then be held in folded position by wrapping the canvas mattress 65 88, which was previously removed,

around such parts and securing it with one or both of the laces 92. When thus compactly folded the bed can be stored away in a small space or readily carried on a motor or other vehicle. From the foregoing it will be understood that there are no entirely removable parts to become lost or misplaced. 70

From the foregoing description it is apparent that I have produced a foldable bed embodying the advantages above pointed out, and while I have shown and described the preferred construction, combination and arrangement of parts, I reserve the right to make such changes as properly fall within the spirit and scope of the claims. 75

Having thus described my invention, what I claim and desire to secure by Letters Patent, is:

1. In a foldable bed, corner posts, side and end rails operably connected at one end to 85 the respective posts to fold against the same or be extended to hold said posts apart, and loops at the other ends of said rails to detachably engage the respective posts.

2. In a foldable bed, four corner posts, 90 side and end rails, rightangular hinges connecting said side and end rails to the respective posts so that they may fold against said posts or be extended to hold the same apart, and loops at the other ends of the rails to 95 engage over the respective posts and the rightangular hinges to lock the same.

3. In a foldable bed, corner posts, side and end rails operably connected at one end to the respective posts to fold against 100 the same or be extended to hold said posts upright, means at the other ends of said rails to detachably engage the respective posts, and foldable stays connected to the posts to assist in holding the same upright. 105

4. In a foldable bed, corner posts, side and end rails operably connected at one end to the respective posts to fold against the same or be extended to hold said posts upright, means at the other ends of said rails to 110 detachably engage the respective posts, braces pivotally connected at their lower ends to the posts, pivots connecting the upper portions of the braces in pairs and spacing each pair apart, and foldable stays extending between 115 the spaced upper portions of said braces and connected to the posts to coact with the rails and the braces in holding the posts upright.

5. In a foldable bed, corner posts, side and end rails operably connected at one end to the respective posts to fold against the same or be extended to hold said posts upright, means at the other ends of said rails to 120 detachably engage the respective posts, braces pivotally connected at their lower ends to the posts, pivots connecting the upper portions of the braces in pairs and spacing each pair apart, foldable stays extending between the 125 spaced upper portions of said braces and 130

connected to the posts to coact with the rails and the braces in holding the posts upright, and means for detachably connecting the braces and said stays together.

5 6. In a foldable bed, corner posts, side and end rails operably connected at one end to the respective posts to fold against the same or be extended to hold said posts upright, means at the other ends of said rails to de-

10 tachably engage the respective posts, braces pivotally connected at their lower ends to the posts, pivots connecting the upper portions of the braces in pairs and spacing each pair apart, foldable stays extending between 15 the spaced upper portions of said braces and connected to the posts to coact with the rails and the braces in holding the posts upright, and studs for detachably connecting the braces and said stays together.

20 7. In a foldable bed, corner posts, side and end rails operably connected at one end to the respective posts to fold against the same or be extended to hold said posts up-

right, means at the other ends of said rails to detachably engage the respective posts, 25 foldable stays connected to the posts to assist in holding the same upright, and foldable guard rails pivoted to the posts and interposed between certain of the rails and stays.

8. In a foldable bed, corner posts, side and end rails operably connected at one end to the respective posts to fold against the same or be extended to hold said posts upright, 30 means at the other ends of said rails to de- tachably engage the respective posts, fold- able stays connected to the posts to assist in holding the same upright, two transverse bars supported by the ends of the stays, and a mattress supported by said bars. 40

In testimony whereof I affix my signature, in the presence of two witnesses.

WILLIAM H. McWILLIAMS.
